UNITED STATES PATENT OFFICE.

JOSEPH H. WALCOTT, OF SALEM, MASSACHUSETTS, ASSIGNOR TO HELBURN THOMPSON COMPANY, OF SALEM, MASSACHUSETTS, A CORPORATION OF MASSACHUSETTS.

LEATHER-WORKING MACHINE.

Application filed June 3, 1924. Serial No. 717,582.

To all whom it may concern:

Be it known that I, JOSEPH H. WALCOTT, a citizen of the United States of America, and resident of Salem, in the county of Essex and State of Massachusetts, have invented new and useful Improvements in Leather-Working Machines, of which the following is a specification.

This invention pertains to the treatment of sheet material and relates more particularly to the finishing and polishing of leather.

In the preparation of fine leathers, for example those employed for bookbindings, bags, etc., one of the final steps in the process consists in rubbing the surface of the skin to impart a slight gloss thereto. This operation is not intended to produce a high gloss such as might be secured by calendering the leather or subjecting it to the action of highly polished and hard rubbing devices, but is designed merely to remove the dullness or dead appearance resulting from previous processes, such for example as embossing, whereby to exhibit the true beauty of texture of the material.

Heretofore this desired slight gloss has been obtained manually, the skin being spread upon a table and its finished surface being rubbed with a felt or other soft and resilient pad held in the hand of the operator until the desired gloss is obtained. This is a slow and laborious operation, and the principal object of the present invention is to provide mechanism for performing this process mechanically and with greater rapidity than it can be performed by hand.

In the accompanying drawings, one desirable embodiment of the invention is illustrated by way of example, and in such drawings,—

Fig. 1 is a plan view, partly broken away, illustrating the invention as embodied in a power driven machine;

Fig. 2 is a side elevation of the machine shown in Fig. 1;

Fig. 3 is a vertical section substantially on the line 3—3 of Fig. 1; and

Fig. 4 is a front elevation of a desirable form of rubbing appliance.

In that embodiment of the invention herein selected for illustration, the operative parts of the machine are mounted upon a table 1 having front legs 2 and rear legs 3.

This table is also provided at its opposite sides at points intermediate its front and rear edges with uprights 4 and 5 respectively, such uprights extending to a point above the upper surface of the table for a purpose hereinafter described.

Brackets 6 are secured to the front legs 2 and provide journal bearings for a shaft 7 carrying a guide roller 7^a so disposed that the upper surface of the table is substantially tangent to the periphery of the roller.

Brackets 8 at the rear end of the table provide journal bearings for a shaft 9 parallel to the shaft 7 and provided with a roll 10 to which the upper surface of the table is also tangent. Preferably the bearings 7^a for one or both of the shafts 7 and 9 should be of adjustable type to permit the rolls 7^a and 10 to be positioned in accurate parallelism and to adjust them to the proper height relatively to the top of the table. Such bearings are well known and form no essential part of the present invention, and therefore are not specifically illustrated.

Brackets 11^b are supported by the uprights 4 and 5 respectively near the lower ends of the latter and provide journalled bearings for a shaft 11 provided with a guide roll 11^a. The bearings for shaft 11 are also preferably adjustable to permit tensioning the belt, hereinafter described, and also to facilitate the removal of the belt.

The shaft 9 which carries the roller 10 is furnished with a sprocket wheel 12 driven by a sprocket chain 12^a passing about the sprocket 13 journalled on a stub shaft 14 carried by a bracket 15 mounted upon the upwardly projecting portion of the upright 4.

An endless belt conveyor 16 passes around the rollers 7^a, 10, and 11^a respectively and comprises an upper horizontal run 17 which extends lengthwise of the top of the table. This belt is desirably of very thin and flexible material so as to yield locally to accommodate very small inequalities in the thickness of the skin during the polishing process.

The table top is provided with an opening 18 extending transversely across from one of the uprights 4 to the other upright 5 and the upper run 17 of the belt bridges this opening.

Immediately above the opening 18 a shaft 19 is journalled in brackets carried by the

upwardly projecting parts of the uprights 4 and 5 respectively. At one end this shaft is provided with a pulley 20 which may be driven by a belt from any suitable source 5 of power. At its other end the shaft 19 is furnished with a gear 22 which meshes with a gear 23 secured to the sprocket 13. A roller 24 is secured to the shaft 19 and is provided with a resilient rubbing surface 10 herein illustrated as consisting of spirally disposed ribs 25 secured to the peripheral surface of the roller. Preferably the ribs 25 are arranged as indicated in Fig. 4 wherein they extend in opposite spirals 15 from a point midway between the ends of the roller, such an arrangement tending in a well known manner to stretch the material laterally as the latter is passed beneath the roller. The bearings for shaft 19 are 20 preferably of adjustable type to permit accurate setting of the roller 24 relatively to the belt 17, and to take up wear in the ribs 25.

The gearing connections between the shaft 25 19 and the shaft 9 are such that the run 17 of the belt 16 moves in a front to rear direction while the opposed surface of the roller 24 moves in the same direction but at a greater surface speed.

30 A shaft 36 is journalled in bearings carried by the uprights 4 and 5 respectively at a point below the table top, this shaft being parallel to and substantially in the vertical plane of the shaft 19. The shaft 26 35 is provided with a roller 27 carrying brush bristles 28 disposed to form a cylindrical brush.

The bristles 28 are of such length that they project up through the opening 18 in 40 the table into contact with the under side of the belt so as to support and press the latter resiliently upward as it passes across the opening 18. The bearings for shaft 26 are preferably adjustable to permit the 45 brush to be set accurately with relation to the belt 17.

In the operation of the machine, the shaft 19 and the belt 16 are driven as above indicated. The operator, standing in front 50 of the machine spreads the skin to be treated upon the surface of the belt 17 and the latter immediately moves the skin rearwardly beneath the rubbing roll 24. As the surface speed of the roll is greater than that 55 of the supporting belt the roll rubs the surface of the leather and imparts the desired gloss thereto. During this action of the rubbing roll the material is pressed upwardly into engagement therewith by the resilient action of the brush bristles 28.

The resilient support thus afforded by the cylindrical brush results in the production of that degree of gloss which is desirable and which has only been attainable heretofore by a manual operation. Moreover it

insures uniformity of action of the action of the rubbing roll even though the skin may vary slightly in thickness from point to point as it avoids the subjection of the non-uniform material to such pressure as 70 might cause the production of streaks or blotches upon the finished surface.

While a rotating roll is herein disclosed as constituting a desirable form of rubbing appliance, it is contemplated that other 75 types of rubber may be substituted therefor and also that in its broadest aspects the invention may include the substitution of other forms of resilient support than that furnished by the brush roll herein illustrated.

It is to be understood that the invention is not confined to the particular embodiment herein disclosed, but that the details of construction may be varied as circumstances 85 may warrant and as the art develops, without departing from the spirit of the broad invention which is herein disclosed.

I claim:

1. A machine for polishing leather comprising a rubbing appliance, means for feeding the leather to the rubbing appliance, and a resilient support for pressing the leather against the rubbing appliance. 90

2. A machine for polishing leather comprising a rubbing appliance, an endless flexible conveyor for feeding the material to the rubbing appliance, and a resilient support for holding the leather against the rubbing appliance. 95

3. A machine for treating sheet material comprising a rotary rubbing roll, a belt conveyor for feeding the material to be treated to the roll, and a roll having a resilient surface for pressing the conveyor and the material resting thereon toward the rubbing roll. 100

4. A machine for polishing leather comprising a frame, a shaft journalled therein, a rubbing roll mounted upon the shaft, a belt conveyor having one run thereof arranged substantially tangent to the surface of the rubbing roll, means for moving the conveyor at a rate less than the surface speed of the roll, and means disposed upon the opposite side of the belt from the roll for resiliently pressing the belt toward the roll. 110

5. A machine for polishing leather comprising a power driven rubbing roller having a resilient surface, a feed belt having a horizontal run arranged below and substantially tangent to the peripheral surface of the roller, means for driving said belt at a speed less than the surface speed of the roller, and a roller having a resilient surface disposed below the belt and supporting the leather at a point opposite to the rubbing roller. 120

6. A machine for use in polishing leather comprising a power driven rubbing roll, the 130

rubbing surface of the roll consisting of resilient peripheral ribs extending in opposite spirals from the center of the roll toward its opposite ends, a horizontal feed belt for presenting the leather to the rubbing roll, and a brush roll below the belt supporting it at a point opposite the rubbing roll.

7. A machine for use in polishing leather comprising a power driven rubbing roller having a resilient surface, a horizontally moving belt for feeding the leather to the rubbing roller, the speed of the belt being less than the surface speed of the rubbing roller; and a brush roll parallel to the rubbing roller and disposed below the belt for supporting the leather immediately below the rubbing roller.

8. A machine for polishing leather comprising a table having horizontal rolls adjacent to its front and rear edges, an endless belt engaging said rolls and having one run extending horizontally over the table top, the latter having a transverse opening in

termidiate its front and rear edges, a rubbing roller mounted upon a transverse shaft 25 arranged above said opening, said roller having a resilient contact surface, the aforesaid run of the belt being substantially tangent to the periphery of the roller, a second shaft parallel to the rubbing roller shaft jour- 30 nalled below the top of the table, said second shaft carrying a cylindrical brush provided with projecting bristles of such lengths that they project up through the opening in the table and engage the under surface of the 35 aforesaid run of belt, power actuated means for driving the rubbing roller shaft, and means for driving the belt so as to move said run thereof in the same direction as the opposed surface of the rubbing roller but at a 40 surface speed less than the surface speed of the latter.

Signed by me at Salem, Massachusetts, this twenty-eighth day of May, 1924.

JOSEPH H. WALCOTT.
